UNITED STATES PATENT OFFICE.

WILLIAM H. FAUBER, OF CHICAGO, ILLINOIS.

CRANK-HANGER.

SPECIFICATION forming part of Letters Patent No. 662,260, dated November 20, 1900.

Application filed October 19, 1898. Serial No. 694,056. (No model.)

To all whom it may concern:

Be it known that I, WILLIAM H. FAUBER, of Chicago, in the county of Cook and State of Illinois, have invented certain new and useful Improvement in Crank-Hangers; and I do hereby declare that the following is a full, clear, and exact description thereof, reference being had to the accompanying drawings, and to the letters of reference marked thereon, which form a part of this specification.

This invention relates to an improved construction in means for connecting the frame-bars of a bicycle with a hanger-sleeve or tubular part in which the crank-shaft bearings are supported.

The invention consists in the matters hereinafter described, and pointed out in the appended claims.

As shown in the accompanying drawings, Figure 1 is a view in central vertical section of one hanger-sleeve, together with the lugs or tubular projections, by means of which the frame members are attached to said sleeve. Fig. 2 is a sectional view taken on line 2 2 of Fig. 1. Fig. 3 is a plan view of the part shown in Fig. 1. Fig. 4 is a side elevation of the central lug separated from the hanger-sleeve. Fig. 5 is a view in side elevation of the lug for the forward frame-bar. Fig. 6 is a similar view of said forward lug, showing the flange thereof in side view. Fig. 7 is a detail section showing a modified construction in the holding-flange of the sleeve.

The parts shown in the accompanying drawings constitute what is commonly known as the "crank-hanger sleeve or bracket," and the same consists of a tube or sleeve A, which constitutes the body of the bracket, and three attached tubular projections or lugs B, C, and D. The sleeve A is adapted to receive the bearing rings or cups of a ball-bearing and to support the same in proper position with respect to each other and the bearing members upon the crank-shaft which is inserted through said sleeve. As herein shown, the sleeve A is provided with internal screw-threads a a' for engagement with corresponding screw-threads on the bearing members or cups; but said sleeve may be otherwise constructed to receive or hold the external bearing members of the crank-shaft bearings, as may be desired or preferred. The lugs B, C,

and D are each of tubular or cylindric form and provided at their ends adjacent to the sleeve A with integral flanges, as indicated on the drawings by B', C', and D'. The said flanges B', C', and D' are curved to conform to the curvature of the external surface of the sleeve A and are fitted accurately thereto. The lugs are joined to the sleeve by soldering or brazing, and the said flanges B', C', and D' afford extended surfaces in contact with the sleeve, which afford a large area in the brazed joints between the lugs and sleeve, and thereby afford an exceedingly strong connection between the same. In order to afford the greatest possible area of contact between the flanges B', C', and D' and the sleeve, said flanges are made of rectangular form, are fitted closely to each other at their meeting edges, and extend laterally on either side of the lugs, so as to cover approximately the entire outer surface of the sleeve. They may, however, be extended to a greater or less distance laterally from the lugs, according to the requirements of the particular case, without departure from my invention. The said flanges B', C', and D' are arranged to meet each other at points between the central and front and rear lugs; but at the lower sides of the lugs B and D said flanges are extended for a considerable distance downwardly along the curved face of the sleeve, so as to give an extended contact-surface at this point. Such extended parts of the flanges might of course meet each other beneath the sleeve; but usually I prefer to insert a curved filling-piece E between the lower ends of the flanges B' and D', so as to give a smooth cylindric form to the sleeve without making said flange B' and D' unduly long at the lower sides of the lugs there attached. The filling-piece E, however, serves mainly to give a finished appearance to the hanger as a whole and is not essential or necessary so far as the general results desired are concerned.

The several lugs B, C, and D are, as shown in the drawings, designed for making what is known as a "flush-joint" frame, and for this purpose are provided with shoulders b , c , d , against which the ends of the frame-tubes abut when the outer parts of the lugs are inserted therein. The presence of such flanges is not, however, necessary, and the

same results will be produced if the lugs be made without said shoulder, in which case the ends of the frame members may and commonly will reach to the outer surfaces of the flanges B', C', and D'. Said lugs B, C, and D, with their integral flanges, are shown as made of drawn metal and the lugs as being provided with partially-closed outer ends or heads.

10 As a further improvement in a hanger-sleeve provided with the features of construction above described, I form upon the end portions of the sleeve A two outwardly-extending circumferential ribs or flanges a^2 15 a^2 , between which the side margins of the flanges B', C', and D' of the lugs are closely fitted. When the said flanges a^2 are first made, they rise from the face of the sleeve a distance somewhat greater than the thickness 20 of the metal forming the lug-flanges, so that when the lugs are placed in position upon the sleeve preparatory to brazing they may be held in position thereon by hammering down or upsetting said flanges or the inner parts thereof into contact with the edges of the said lug-flanges. To facilitate this operation, I make the sleeve-flanges a^2 25 with relatively thin edges or lips a^3 a^3 , Fig. 2, which may be easily bent over the lug-flanges 30 at the time of securing them in place. The flanges a^2 made as described obviously not only serve to hold in place the several lugs during the operation of brazing, but they also serve as guides to accurately hold the lugs in 35 the same vertical plane, and when the parts are finished form smooth or continuous edges at the side margins of the sleeve, it being of course understood that after the brazing operation is completed said flanges will be filed 40 or otherwise reduced until flush with the adjacent surfaces of the lug-flanges.

A variation in the angular location or position of the lugs B, C, and D is often required in making frames of different styles 45 or proportions, and such variations in the position of the lugs is readily accomplished in the construction described by making the lug-flanges wider or narrower or by originally constructing those on the central lug of 50 a width equal to the greatest that may be required in any case and then reducing same by filing. Moreover, where a considerable difference in the angle of the lug is required, as in making a drop-frame or lady's wheel, a 55 lug made like the lugs B and D illustrated may be reversed, so as to bring the longer part of the flange uppermost, so that it will reach to the flange of the central lug C.

When the article made as described is 60 manufactured and sold as a separate part or fitting, the lugs will usually not be brazed to the sleeve, the attachment of the lugs to the sleeve being in such instance performed by the person who makes the frame and who 65 will braze the lugs to the sleeve at the same time the frame members are secured to the lugs. When the article is thus supplied, the

detached lugs may be readily secured in place upon the sleeve by slightly hammering down or bending over the flanges a' sufficiently to 70 engage and hold the lug-flanges and the article thereby furnished with the parts connected, although the lugs will be left sufficiently loose to be accurately adjusted to place preparatory to brazing.

A hanger-sleeve or bracket made as herein described has many important advantages. A principal advantage is that it is very strong, because the sleeve itself is complete or continuous, while the extended contact-surfaces 80 between the lug-flanges and the sleeve afford brazed joints of ample strength. Another important advantage is that it is very cheap to manufacture, because the central sleeve can be easily or cheaply made, and the flanged 85 lugs being made separately can be easily and rapidly made of drawn metal. Another important advantage arising from the construction described is that the lugs can be readily adjusted into position upon the sleeve to 90 agree with the angles of the frame-members which are to be joined thereto, so that with a single set of forming-tools brackets can be supplied for frames of different designs or proportions.

The employment of holding-flanges a' on the sleeve is of great benefit, for the reason that it greatly simplifies and facilitates the brazing operation, it being obvious that the presence of said flanges makes it unnecessary to join the parts prior to brazing by holding pins or rivets or by the use of wire or other expedients, which are both troublesome and increase the work required in finishing the article after the brazing operation. The employment of the thin edge or lip a on the holding-flange is of especial advantage, as such edge or lip can be easily closed or bent 100 down over the flanges on the lugs by a few blows of a hammer or by the use of other suitable implement, thereby enabling the lugs to be attached to the sleeve by a simple operation, which can be quickly performed. Moreover, such thin lip or flange can be easily 105 and quickly removed by filing or like process 110 after the brazing operation or in the process of finishing the hanger-sleeve.

In Fig. 7 I have shown a construction in the hanger-sleeve in which the holding-flange a' is made of slightly different shape from that shown in the other figures, said flange in this instance being undercut or made to slightly overhang the adjacent surface of the sleeve, while the side margins of the lug-flanges are shaped to conform to the overhanging surface of the flange, which in the instance illustrated is made oblique; so that both flanges together form what is equivalent to a dovetailed groove. When the sleeve is thus constructed, the overhanging part of one or both 120 flanges will be cut away at one point in the circumference of the sleeve (preferably at the lower part thereof) to permit the convenient insertion of the lugs or the engage- 125

ment of the flanges thereof with the holding-flanges. In this construction obviously the overhanging holding-flanges will retain the lugs in contact with the sleeve during ship-
5 ment and while the brazing operation is be-
ing performed. If desired, the lugs may be secured from sliding movement after they have been brought to their proper position by strokes of the hammer upon the over-
10 hanging part of the flange, so as to close the latter against the lug-flanges, and thereby hold the lugs firmly from movement in either direction.

I claim as my invention—

- 15 1. A crank - shaft hanger comprising a hanger-sleeve and a plurality of radial tubu-
lar lugs, each made of a single piece of sheet metal and the lugs being provided at their inner ends with continuous flanges, the
20 flanges of each lug being independent of the flanges of the others, which are curved to fit the outer surface of the sleeve and abut against each other end to end and extend from said lugs toward the ends of the sleeve
2. so as to cover substantially the entire outer surface of the sleeve, said flanges affording independent angular adjustment of said lugs prior to their permanent attachment to the sleeve.
30 3. A crank - shaft hanger comprising a hanger-sleeve and a plurality of radial tubu-
lar lugs, each made of a single piece of sheet metal, and the lugs being provided at their inner ends with continuous flanges, the
35 flanges of each lug being independent of the flanges of the others, which are curved to fit the outer surface of the sleeve and abut against each other end to end and extend from said lugs toward the ends of the sleeve
40 so as to cover substantially the entire outer surface of the sleeve, thereby affording independent angular adjustment of said lugs prior to their permanent attachment to the sleeve, and said sleeve being provided with
45 circumferential holding-flanges adapted for engagement with the side edges of the flanges on the lugs.

3. A crank - shaft hanger, comprising a hanger-sleeve and a plurality of drawn-metal

tubular lugs, provided with outwardly-ex- 50 tending integral flanges which are curved to fit the outer surface of the sleeve, and which abut against each other end to end, thereby affording independent angular adjustment of the lugs prior to their permanent attachment 55 to the sleeve, said sleeve having circumferential holding-flanges, adapted for engage-
ment with the side edges of the flanges on the lug, said holding-flanges being provided with thin edges or lips which rise above the 60 surface of the flange on the lug, and which are adapted to be bent or folded over the same to hold the lug upon the sleeve.

4. A crank - shaft hanger, comprising a hanger-sleeve, and a plurality of lugs having 65 at their outer ends integral heads and at their inner ends flanges which extend radially out-
wardly from all sides thereof, and are curved to fit the outer surface of the sleeve and which abut against each other end to end, thereby 70 affording independent angular adjustment of said lugs prior to their permanent attachment to the sleeve, said sleeve being provided at its opposite ends with circumferential hold-
ing-flanges, and said flanges on the lugs be- 75 ing shaped at their edges to fit against each other and against the holding-flanges of the sleeve.

5. A crank - shaft hanger comprising a hanger-sleeve and a plurality of radial lugs 80 each of which is provided at its inner end with flanges extending radially outwardly from all sides thereof and curved to fit the outer surface of the sleeve, the flanges of each lug being independent from the flanges 85 of the others and constructed to afford independent angular adjustment of said lugs prior to their permanent attachment to the sleeve.

In testimony that I claim the foregoing as 90 my invention I affix my signature, in presence of two witnesses, this 21st day of September, A. D. 1898.

WILLIAM H. FAUBER.
